VERN REED PETTY, OF BROOKLYN, NEW YORK

COMBINED FUEL MEASURING PUMP AND FUEL FEED VALVE FOR INTERNAL COMBUSTION ENGINES

Application filed September 30, 1926. Serial No. 138,800.

My invention relates to a combined fuel measuring pump and fuel feed valve for internal combustion engines for measuring and injecting liquid fuel at high pressure, without the use of compressed air, directly into the cylinder of internal combustion engines.

The general object of my invention is to provide a device of the indicated purpose in which the fuel valve and fuel measuring pump are combined in a single unit whereby various advantages result as will appear.

The nature of the invention and its distinguishing features and advantages will be clearly understood as the description proceeds.

Reference is to be had to the accompanying drawing forming part of this specification, in which the figure represents a vertical section of a combined fuel measuring pump and fuel feed valve embodying my invention, it being understood that the drawing is merely illustrative of one example of the invention.

In carrying out my invention in practice in accordance with the illustrated example the device includes a body 10 having at one end thereof a fuel discharge opening or openings 11, here shown as in a separate element 13, held by a cap 12. Element 13 is formed with a suitable valve seat 14. Extending upwardly from the valve seat 14 is a fuel feed passage 15 in which operates a spindle valve 16 having an enlarged upper end 17 to provide an enlarged zone 18. The passage 15 communicates at the top with a chamber 19 having a fuel inlet 20. Set also at the top is a bleeding cock 21 or equivalent bleeding means. Bearing on the upper end of fuel valve 16 is a separate cap 22 under the pressure of a spring 23 coiled about the stem or reduced end 24 of a plug 25 which screws into the body 10, closing the chamber 19 at the top.

A measuring and force pump plunger 26 extends into a fuel passage 27 having a side inlet port 28 from chamber 19 and thereby adapted to receive fuel delivered to said chamber 19 from inlet 20. Pump plunger 26 has a head 29 against which bears a spring 30 coiled about said plunger 26. Spring 30

and head 29 operate in a chamber 31 into which the plunger 26 extends. The numeral 32 indicates a drain cock for chamber 31. The plunger 26 is subject to a reciprocating movement of a tappet 33 operated by a suitable cam device 36 here conventionally shown, said cam device operating against the head 34 of tappet 33. Spring 35 bears against head 34 and against body 10, tending to lift the tappet 33 when permitted to do so by the revolution of the cam 36. Liquid fuel is supplied at a moderate pressure of 25 to 30 pounds to the square inch through inlet 20, thereby filling the chamber 19 as well as the passages 27 and 15. Any air carried in with the fuel or trapped in the interior of the device will rise to the upper part of chamber 19 and may be bled off to the atmosphere by means of the cock 21 or other bleeding device. Pump plunger 26, upon being moved toward passage 15 under pressure of tappet 33 and cam device 36 will close the port 28, thereby causing an immediate rise in the pressure of the liquid fuel trapped in the passages 27 and 15. The increase of pressure lifts the fuel valve 16 away from its seat 14 by reason of the different diameters at the end of the fuel valve and at the zone 18. The continued movement of the plunger 26 at closing port 28 will force the liquid in the passages 27 and 15 through the discharge openings at 11, and into the engine cylinder. The plug 25 and its stem 24 act as a stop to limit the upward movement of the fuel valve 16. As will readily be understood the pressure at the point of discharge into the cylinder at the opening 11 is determined by the size of said opening at 11 and the tension of spring 23. The finely atomized liquid fuel emerging from the opening 11 into the cylinder may, as will be readily understood, be ignited by the heat of combustion alone, as in the high compression "Diesel" type of engine or by a heated surface as in the medium compression, surface ignition, semi-Diesel engine, or by an electric sparking device as in a gasoline engine. The described assemblage functions in a manner that the various passages of the fuel chamber proper and the fuel valve chamber auto-

5 matically clear themselves of entrained air in the fuel, as the air will rise in the upper part of the chamber 19 where it will not affect the operation of the pump. I would state that the pressure carried in the chamber 19 is such that the pump channel 27 will be instantly filled through the port 28 as the pump plunger 26 is withdrawn and uncovers said port 28.

10 During the revolution of the cam device 36 the tappet 33 will be relieved of the cam pressure and will allow said tappet 33 and plunger 36 to be moved outward by the springs 30 and 35, which will result in a drop in the 15 pressure of the fuel in the passages 27 and 15. The drop in pressure in said passages 27 and 15 allows fuel valve 16 to be returned to its seat 14 by the spring 23. The continued upward movement of pump plunger 20 26 causes a partial vacuum in the passages 27 and 15, until port 28 is uncovered, when the vacuum is broken and said passages are again filled with fuel from the said chamber 19.

25 The advantages of the above described assemblage will be apparent, as follows:

It combines fuel valve and fuel measuring pump in a single unit; it eliminates the massive and costly measuring pumps generally 30 used; the device may be cheaply and simply manufactured; the use of a check valve as commonly used in the fuel pump is eliminated; all high pressure piping connecting fuel measuring pumps and fuel valves as 35 ordinarily arranged is eliminated; no high pressure is developed in the device except during the delivery stroke of the pump; the pressures possible of attainment for injecting the fuel are much higher than 40 in the systems usually employed; the higher pressures cause the fuel to break up and be more finely atomized upon its escape into the cylinder, thereby giving better combustion; the danger of those parts subjected to high 45 pressure leaking or bursting is eliminated; fuel valve 16 operates quickly, cutting off the fuel jets at the discharge opening 11 sharply upon the valve closing, which prevents the forming of a drop at the discharge opening 50 with the effect of after burning, which is the case when the common type of slow-closing fuel valve is used; the device eliminates the trouble caused by air pockets so common in systems of this general character, because 55 even though considerable air might collect in the upper part of the chamber 19 it would not affect the operation of the pump plunger; the amount of fuel delivered is easily controlled by varying the amount of inward 60 movement of the pump plunger 26 by suitable variation in the cam motion of the device 36; the device is particularly suitable for very small cylinders, as it will measure and deliver small quantities of fuel accurately; the fuel 65 valve 16 is lifted well away from its seat 14,

thus preventing the cutting of the seat by the high velocity of the flowing fuel, which is a common trouble in the present systems; the device will operate quite successfully at 70 high speed; and finally, it will not easily get out of adjustment, as is the case with systems now in use.

In the operation of the device, the passages 15 and 27 constitute the measuring 75 chamber.

I would state furthermore that while the illustrated example constitutes a practical embodiment of my invention, I do not limit myself strictly to the exact details herein illustrated, since, manifestly, the same can be 80 considerably varied without departure from the spirit of the invention, as defined in the appended claim.

What I claim is:

A combined fuel measuring pump and fuel 85 feed valve for internal combustion engines, comprising a body having a vertical portion, a supply chamber in the upper part thereof and a discharge chamber in the lower part thereof, an integral angularly related portion containing a pressure chamber communicating with said supply and discharge chambers and also containing a recess located above said pressure chamber, a plunger slidably mounted in said pressure chamber and 90 extending into said recess, said plunger having a shoulder, a coil spring on said plunger and bearing against said shoulder, means for actuating said plunger, an oil bleeder valve communicating with the lowermost part of 100 the recess, an air bleeder valve communicating with the uppermost part of said supply chamber, a supply tube communicating with said supply chamber, a valve located in said discharge chamber and having a smaller 105 diameter than said chamber, an enlarged portion of said valve extending into said supply chamber and means for urging the valve to closed position.
